CLAIM

The ornamental design for a suitcase, as shown and described.

DESCRIPTION

The file of this patent contains at least one drawing/photograph executed in color. Copies of this patent with color drawing(s)/photograph(s) will be provided by the Office upon request and payment of the necessary fee.

4.1: Perspective view of a suitcase showing the new design;

4.2: Front view thereof;

4.3: Back view thereof;

4.4: Top view thereof;

4.5: Bottom view thereof;

4.6: Left view thereof; and

4.7: Right view thereof.

The shading and tone in the reproductions are to represent the relief or contours of the surfaces of the three-dimensional products. The parts shown by means of red coloration are not part of the claimed design.
